COMBINATION LOCK SWITCH

Edward Jackman Tobin, Norfolk, Conn.

Application June 15, 1949, Serial No. 99,299

6 Claims. (Cl. 200—43)

1

The present invention relates to new and useful improvements in switches and more particularly to a combination lock switch suitable for use as an ignition switch for motor vehicles, as well as for controlling other electrical circuits.

An important object of the invention is to provide an improved lock for the ignition switch of a motor vehicle which reduces the liability of theft and eliminates the use of key-controlled switches and the accompanying objections thereto, such as the danger of losing the key or breaking off the key in the lock.

Another object is to provide a switch closed by an initial sliding action and controlled by a permutation or combination lock mechanism with independent means for locking the switch in its closed position and released by a subsequent sliding action of the switch.

A further object is to provide a device of this character of simple and practical construction, which is efficient and reliable in operation, relatively inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal sectional view showing the switch open;

Figure 2 is a similar view showing the switch closed;

Figure 3 is an enlarged perspective view of the expandible sleeve for locking the switch in closed position and with parts shown in section;

Figure 4 is a fragmentary longitudinal sectional view showing the locking sleeve in position for releasing the switch;

Figure 5 is a front elevational view of the dial for the combination lock;

Figures 6 and 7 are transverse sectional views taken respectively on the lines 6—6 and 7—7 of Figure 1;

Figures 8 and 9 are transverse sectional views taken respectively on the lines 8—8 and 9—9 of Figure 2; and

Figure 10 is a transverse sectional view taken on a line 10—10 of Figure 4.

Referring now to the drawings in detail, wherein, for the purpose of illustration, I have disclosed a preferred embodiment of my invention, the numeral 5 designates a dial having a forwardly projecting hollow handle or knob 6. A hub 7 projects from the rear face of dial 5 and to which

2

one end of a drum 8 is secured by means of an internally beveled ring 8a threaded on the hub. The drum 8 is positioned at the rear of a panel 9, such as the instrument panel of a motor vehicle, and the drum rotates in an opening 10 in the panel. An escutcheon plate 11 is fixed to the front of panel 9 behind dial 5 and is provided with a zero setting 12 for use with the indicia 13 appearing on the dial.

10 A push rod 14 is slidably mounted in handle 6 to project forwardly thereof and projects rearwardly through an opening 15 in the rear end of drum 8 and is formed with a reduced rear end 16 extending slidably through a collar 17 fixed in a tubular housing 18 which is formed with an enlarged front end 19 enclosing drum 8 and suitably secured at the rear of panel 9.

The rod 14 is provided with a front lug 20 and rear lug 21 sliding in a longitudinal slot 22 in a sleeve 23 positioned on the rod. A disk 24 is held on sleeve 23 between a pair of resilient split retaining rings 25 frictionally embracing the sleeve and frictionally engaging or otherwise fixed to the disk, the disk having an internal opening 26 through which the front lug 20 is slidably and also having a radial lug 27 on its periphery engaging an internal lug 28 on the inside of drum 8.

The opening 15 in the rear end of drum 8 is provided with a notch or passage 29 through which the rear lug 21 is movable.

30 Rod 14 is provided with a pin or lug 30 sliding in a longitudinal slot 31 in sleeve 23 and engaging the front end of a coil spring 32 surrounding sleeve 23 and retained on the rear end of the sleeve by a rear washer 33 held on the sleeve by a lip 34. A larger coil spring 35 is held between rear washer 33 and a front washer 36 suitably secured to drum 8.

A disk 37 of conductive material is secured to the rear end of rod 14 and insulated therefrom by a washer 38 with a pair of conductor prongs 39 projecting from the outer face of disk 37 for entering a pair of sockets 40 secured in an insulation block 41 suitably held in housing 18. The sockets 40 are provided with terminals 42 for attaching circuit wires 43 thereto, such as the ignition circuit of a motor vehicle.

The collar 17 is formed with an enlarged chamber 44 in which a ring 45 is loosely positioned and surrounding reduced end of rod 14. A contractible sleeve 46 is formed with a tapered rear end 47 suitably secured on rod 14 for movement therewith and the front end of sleeve 46 is provided with longitudinal slits 48 to permit expansion and contraction of the sleeve. The opening in the 50 collar 17 is of suitable diameter to admit sleeve

46 during sliding movement of rod 14 and the sleeve 46 enters chamber 44 upon a forward movement of the rod.

The rod 14 and sleeve 23 are held from turning movement by a sleeve 49 secured in housing 18 between collar 17 and block 41 and in which the disk 37 and washer 38 are slideable. The sleeve 49 is formed of insulation material to prevent shorting from the disk 37 to the housing 18 and with internal longitudinal ribs 50 seated in grooves 51 in the periphery of the disk 37 and washer 38. The prongs 39 on disk 37 are thus held in alignment with sockets 40 during sliding movement of rod 14.

Sleeve 23 is held from turning movement on rod 14 by pin 38 and slot 31 and sleeve 23 is held from sliding movement by a beveled disk 52 secured to the front end of sleeve 23 and positioned against the beveled edge of ring 8a.

In the operation of the device, rod 14 and sleeve 23 are held from rotation by grooves 51 carried by washer 38 fixed to the rod and ribs 50 on sleeve 49 fixed to housing 18. Rod 14 slides in sleeve 23 to make and break the circuit by prongs 39 sliding in and out of sockets 40.

The rod 14 is held outwardly by spring 32 engaging pins 33 to break the circuit and releasing lugs 20 and 21 from the openings in disk 24 and inner end of drum 8 whereupon the drum may be turned by handle 6 of dial 5 to lock the rod 14 from inward movement by moving the opening in the inner end of the drum out of alignment with lug 21 and the turning of drum 8 also engages lug 28 of drum 8 with lug 27 of disk 24 to also move the opening in the disk out of alignment with lug 20, the disk being rotatable on sleeve 23. The rod cannot be pushed inwardly until handle 6 and dial 5 are turned in a proper direction to again engage lug 28 with lug 27 to rotate disk 24 until its opening is again aligned with lug 20 and to subsequently turn handle 6 and drum 8 in an opposite direction while disk 24 remains stationary and until opening in drum 8 is again aligned with lug 21, this initial and subsequent aligning movement of the disk and drum being determined by the registering of predetermined indicia on dial 5 with the zero setting or mark 12.

With the handle 6 and dial 11 turned in proper relation for inward, rearward movement of the rod 14, said rod is shoved inwardly, part way, as shown in Figure 2 in opposition to the spring 32. This shoves the contractile sleeve 46 into the chamber 44 and the conductor prongs 39 part way into the sockets 40 to close the circuit. As soon as the contractile sleeve 46 enters the chamber 44, it expands, as shown in Figure 2, so that it cannot be retracted out of said chamber and whereby the rod 14 is locked against outward movement, forwardly, for the purpose of breaking the circuit closed at the prongs 39 and sockets 40. As the contractile sleeve 46 assumes the described locking position, it enters the ring 45 which is wedged upon the tapered end 47 of said sleeve 46 and carried thereby against the rear wall 46' of said chamber 44 as shown in Figure 2.

To unlock the rod 14 for outward, forward sliding movement, said rod is shoved inwardly further, as shown in Figure 4, whereupon the ring 45 will be forced against the rear wall 46' of the chamber 44 to be slid further onto the sleeve 46 and thereby contract said sleeve so that it can be retracted out of the chamber 44 as shown in Figure 10. As the sleeve 46 is retracted, the ring

45 will engage the front wall 47' of the sleeve 46 and be stripped off said sleeve.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A combination switch comprising a casing, a stationary contact in the casing, a sliding contact in the casing movable into and out of engagement with the stationary contact, a rotary member controlling movement of the sliding contact, and means separate from said rotary member automatically locking and releasing the sliding contact by successive movements of the sliding contact while engaged with the stationary contact.

2. A combination switch comprising a casing, a stationary contact in the casing, a sliding contact in the casing movable into and out of engagement with the stationary contact, a rotary member controlling movement of the sliding contact, and means separate from said rotary member automatically locking the sliding contact by an initial contacting movement thereof and automatically releasing the sliding contact by a subsequent contacting movement thereof in the same direction.

3. A combination switch comprising a casing, a stationary contact in the casing, a sliding contact in the casing movable into and out of circuit making and breaking engagement with the stationary contact, a rotary permutation controlled locking member for holding the sliding contact in circuit breaking position, and means automatically locking the sliding contact in circuit making position upon an initial circuit making movement thereof and subsequently releasing the sliding contact for breaking the circuit upon a continued circuit making movement thereof comprising an apertured stop, an expansible and contractible locking member on the sliding contact movable through said stop and expanding behind the same upon initial circuit making movement of said sliding contact to lock the sliding contact, and devices for contracting said locking member upon continued circuit making movement of said sliding contact.

4. A combination switch comprising a casing, a stationary contact in the casing, a sliding contact in the casing movable into and out of circuit making and breaking engagement with the stationary contact, a rotary permutation controlled locking member for holding the sliding contact in circuit breaking position, means automatically locking the sliding contact in circuit making position upon an initial circuit making movement thereof and subsequently releasing the sliding contact for breaking the circuit upon a continued circuit making movement thereof, said automatic locking means comprising an expansible locking member carried by the sliding contact, a ring for contracting the expansible member and slidably carried thereby, a pair of spaced apart movement-limiting stops for the ring fixed

in the casing, said expansible member engaging one of the stops to lock the sliding contact in circuit making position and said ring remaining inactive during initial circuit making movement of the sliding contact and engaging the other of said stops for movement thereby into a position for contracting the expansible member during subsequent circuit making movement of the sliding contact to release the latter for circuit breaking movement.

5. A combination switch comprising a casing, a stationary contact in the casing, a sliding contact in the casing movable into and out of circuit making and breaking engagement with the stationary contact, a rotary permutation controlled locking member for holding the sliding contact in circuit breaking position, and means automatically locking the sliding contact in circuit making position upon an initial circuit making movement thereof and subsequently releasing the sliding contact for breaking the circuit upon a continued circuit making movement thereof, said automatic locking means comprising an expansible locking member carried by the sliding contact, a chamber in the casing and in which the expansible member is locked when the contacts are closed, and a captive ring in the chamber for contracting the expansible member to release the same from the chamber, said ring being inactive during initial circuit making movement of the sliding contact and wedged onto the expansible member to contract the latter during subsequent circuit making movement of the sliding contact.

6. A combination switch comprising a stationary mounted contact, a slidably mounted contact slidably movable into and out of engagement with the stationary contact, and means automatically locking the slideable contact by an initial contacting movement thereof and automatically releasing said sliding contact by a subsequent contacting movement thereof in the same direction comprising an apertured stop, an expansible and contractible locking member on the slideable contact movable through said stop and expanding behind the same upon initial circuit making movement of said slideable contact to lock the slideable contact, and devices for contracting said locking member upon continued circuit making movement of said slideable contact.
